UNITED STATES PATENT OFFICE.

GEORGE STEELE TIFFANY, OF SUMMIT, NEW JERSEY, ASSIGNOR TO THE GRAY NATIONAL TELAUTOGRAPH COMPANY, OF NEW YORK, N. Y., A CORPORATION OF VIRGINIA.

TELAUTOGRAPH.

954,062.

Specification of Letters Patent.

Patented, Apr. 5, 1910.

Original application filed February 5, 1906, Serial No. 299,413. Divided and this application filed May 16, 1907. Serial No. 374,037.

To all whom it may concern:

Be it known that I, GEORGE S. TIFFANY, a citizen of the United States, residing at Summit, county of Union, and State of New Jersey, have invented certain new and useful Improvements in Telautographs, fully described and represented in the following specification and the accompanying drawings, forming a part of the same.

10 The invention of this application (a division of my application filed February 5, 1906, Serial No. 299,413) relates to improvements in relays for electric circuits.

Although devised with especial reference 15 to telautographic systems, the improvements of the present invention are capable of application to other systems employing a main line circuit and another circuit the condition of which is controlled thereby 20 through a relay, as will be apparent from the detailed description of the present invention, which will now be given in connection with a telautographic system.

In the accompanying drawings—Figures 25 1 and 2 illustrate, mainly in diagram, two stations of a telautographic system, each equipped with a relay embodying the present invention. Figs. 3, 4 and 5 are details, upon an enlarged scale, of the master switch, 30 with which each station is provided. Fig. 6 is a vertical section, on an enlarged scale, of the relay illustrated in Figs. 1 and 2. Fig. 7 is a bottom view of said relay; and Fig. 8 is a cross section, on the line 8 of 35 Fig. 6, of a circuit closing device forming part of the relay.

The telautographic apparatus illustrated in the drawings is of the type in which the movements of the receiving pen of the 40 distant station in unison with the transmitting tracer of the station from which messages are being transmitted to said distant station, are effected by variations in the strength of the currents sent to line from 45 the transmitting instrument to the receiving instrument, such variations in current strength being in turn effected by and corresponding to the movements of the transmitting tracer. The particular apparatus 50 illustrated in said drawings is identical with that illustrated and described in detail in my prior application aforesaid, except that here some of the devices and circuit connections which appear in the drawings of my

said prior application have been omitted for 55 clearness and because illustration thereof in the present case is unnecessary. Except for the relay constituting the present invention and the circuits and devices controlled thereby, the telautographic apparatus shown 60 herein need only be described briefly, reference being made to my said prior application for a more detailed description of it.

Each station of the telautographic apparatus shown comprises a transmitting instrument (designated 1 in Fig. 1 and 1^a in Fig. 2), a receiving instrument (designated 2 in Fig. 1 and 2^a in Fig. 2), an oscillatory master switch (designated 3 in Fig. 1 and 3^a in Fig. 2) for connecting the transmitter or receiver of its station with the receiver or transmitter, respectively, of another station, or connecting together the receiver and transmitter of its own station for "testing," and a battery (designated 4 in Fig. 1 and 4^a in Fig. 2) from which, when the station is transmitting, currents, varying in strength in accordance with the movements of the transmitting tracer, are shunted into the main line circuits connecting the transmitting instrument with the receiving instrument 65, which it is transmitting, and which battery also serves as a local battery for the circuits of the receiving instrument when the latter is 70 "receiving." As the devices and circuits at 75 one station are identical with those at another station, a description of one transmitting instrument and one receiving instrument will be sufficient. The transmitting instrument of Fig. 1 and the receiving instrument of Fig. 2 will be selected for such description. The same reference numerals will be applied to corresponding parts in Figs. 1 and 2, except that, for convenience of description, reference letter "a" will be added 80 to the reference numerals in Fig. 2.

The transmitting instrument (Fig. 1) is provided with the usual depressible writing platen 5 on which the writing instrument or tracer 6 rests in transmitting, the usual paper strip (not shown) on which the tracer makes its record being fed over this table by paper shifting mechanism such as shown and described in my prior application aforesaid. The tracer 6 is pivotally mounted in the converging ends of a pair of hinged arms 7, 8, the opposite ends of which are pivoted to the outer ends of a pair of arms 9, 10 pivotally 100 105 110 115 120 mounted at 11 so as to oscillate freely in a horizontal direction, and provided with a second pair of arms 12, 13, respectively, (from which they are suitably insulated) 5 having at their outer ends spring plates in which are journaled roller contacts 14, 15, respectively, which, as the arms or bell crank levers 9, 12 and 10, 13 are oscillated by the movement of the transmitting tracer 6, 10 move back and forth between the opposite ends of a pair of rheostats 16, 17, respectively. These rheostats are in circuit at their opposite ends with battery 4 so that when the circuits connecting them with said battery 15 are closed, currents are shunted through the rheostats 16, 17 and arms 12, 13 into the main line circuits leading from the transmitting instrument to the distant receiver; these currents varying in strength in accordance with 20 the positions assumed by the roller contacts 14, 15 between the ends of said rheostats.

One end of rheostat 16 is at all times connected by wires 18, 19 with the negative pole of battery 4, and the corresponding end of 25 rheostat 17 is also connected therewith by wires 20, 19; this pole of the battery being grounded, as shown, so that the currents supplied by said battery to the main line circuits, or when it is serving as the local battery 30 of the receiver, are positive. Normally the master switch 3 occupies the position in which it is shown in Fig. 3, and in this position of the master switch the transmitter of the station is "off" and the receiver of 35 that station is "on," or ready to receive messages, and in this position of the switch the opposite or smaller ends of the rheostats 16, 17 are not connected with the positive pole of battery 4. When, however, the master 40 switch is rocked forward from the position shown in Fig. 3 to the position shown in Fig. 4, these ends of the rheostats 16, 17 are connected with the positive pole of battery 4,—rheostat 16 by wires 22, 23, contacts 24, 45 25, contact plate 26 (carried by switch 3 and which in this position of said switch electrically connects said contacts 24, 25), and wire 27 to the positive pole of battery 4, and the rheostat 17 by wires 28, 23, contact 24, 50 plate 26, contact 25 and wire 27 to the positive pole of battery 4. In this position of the master switch also two contact plates 29, 30 carried by and suitably insulated from master switch 3 close the main line circuits 55 from the transmitting instrument to the receiving instrument of the distant station, plate 29 by engaging and electrically connecting a pair of upper and lower contacts 31, 32 in the right hand main line circuit, 60 and plate 30 by engaging and electrically connecting a pair of upper and lower contacts 33, 34 in the left hand main line circuit. With the switch 3 in this position, the right hand main line circuit from the transmitting station (Fig. 1) consists of arm 12,

wire 35, right secondary winding 36 of an induction coil, (the function of which will be hereinafter pointed out) wire 37, contact 31, plate 29, contact 32, and wire 38 leading to the right hand side of the receiving instrument (Fig. 2); while the left hand main line circuit consists of arm 13, wire 39, left secondary winding 40 of the induction coil just referred to, wire 41, contact 33, plate 30, contact 34, and wire 42 leading to the 75 left hand side of the receiving instrument (Fig. 2).

At the time the master switch 3 of Fig. 1 is thus shifted to transmitting position, the master switch 3^a of the distant station being 80 in its normal position,—that is, with the transmitter of that station "off" and the receiver thereon "on,"—the contact plate 26^a of switch 3^a will be out of engagement with contacts 24^a, 25^a so that the circuits from 85 battery 4^a through rheostats 16^a, 17^a of that station (Fig. 2) are open. In this position of the master switch 3^a, also, its plates 29^a, 30^a are lowered out of engagement with upper contacts 31^a, 33^a, respectively, and into 90 engagement with the two contacts 43^a, 44^a, respectively, (see Fig. 4), contact 43^a being electrically connected by plate 29^a with under contact 32^a; and contact 44^a by plate 30^a with under contact 34^a.

With the master switch 3^a in this position, the right hand main line circuit of Fig. 1 entering and passing through the receiving instrument 2^a of Fig. 2, consists of line wire 38^a (continuation of wire 38 of Fig. 1), 100 contact 32^a, plate 29^a of master switch 3^a, contact 43^a, wire 45^a, vertically movable coil 46^a on the right hand side of the receiving instrument, and wires 47^a, 48^a leading thence to ground at 49^a (Fig. 2) and back to the 105 negative pole of battery 4 (Fig. 1); while the left hand main line circuit consists of wire 42^a (continuation of wire 42 of Fig. 1), contact 34^a, plate 30^a of master switch 3^a, contact 44^a, wire 50^a leading therefrom through the winding of a combination relay 110 51^a (embodiment the present invention), wire 52^a leading therefrom to a vertically movable coil 53^a at the left hand side of the receiver, and wires 54^a and 48^a leading thence 115 to ground at 49^a (Fig. 2) and back to the negative pole of battery 4 (Fig. 1). The coils 46^a, 53^a, just referred to, fit loosely over the vertical cores 55^a of the field magnet 56^a, and normally are at the upper ends of said 120 cores, in which position they are held by chains 57^a and springs 58^a.

In the normal position, just described, of the master switch 3^a, with the transmitter "off" and the receiver "on," battery 4^a of 125 Fig. 2 serves as a local battery for the receiving instrument, one of the functions performed by it being the energization of magnet 56^a, the circuit through which it does this work consisting of wire 27^a from the 130

positive pole of battery 4^a, wire 59^a, magnet 60^a (which, as described in my said prior application, locks master switch 3^a in its normal position while current is on the left hand main line circuit), wire 61^a to magnet 56^a, wire 62^a leading from said magnet to a contact plate 63^a carried by but insulated from armature 64^a of relay 51^a, contact 65^a for plate 63^a, and wire 66^a leading therefrom to the negative pole of battery 4^a and ground. When the master switch 3^a is in the normal position just described and current is passing over the left hand main line circuit from battery 4 of the transmitting 10 instrument (Fig. 1), the relay 51^a, through which this circuit passes, will be energized, and attract its armature 64^a, which will cause plate 63^a to engage contact 65^a and thus close the circuit just described through 15 magnet 56^a from battery 4^a, and this local circuit will remain closed so long as there is any current on the left hand main line circuit.

With the master switch 3 of Fig. 1 in the 20 position shown in Fig. 4, that is, so that the receiver of that station is "off" and the transmitter thereof "on", and with the master switch 3^a of Fig. 2 in the position shown in Fig. 3, that is, so that the transmitter of that station is "off" and the receiver thereof "on", the main line circuits from the transmitter of Fig. 1 to the receiver of Fig. 2 will be closed with current passing over them from battery 4.

35 The operation of the apparatus, briefly described, will then be as follows: The operator of the transmitter (Fig. 1) will raise the transmitting tracer from its resting place in unison position (see Fig. 2), and move it laterally to a position over the writing platen 5, then lower it so that its point will rest upon the paper strip (not shown) passing over said platen, and then move the tracer over the paper to inscribe thereon the 40 message to be transmitted. As the tracer 6 is thus moved laterally from unison position and over the surface of the paper, the roller contacts 14, 15 will be moved by the arms 9, 12 and 10, 13, respectively, to different positions between the opposite ends of the rheostats 16, 17, respectively. As the roller contacts are thus moved, currents, varying in 45 strength in accordance with the different positions assumed by said roller contacts along the rheostats 16, 17, will be shunted through the said rheostats and the arms 12, 13 into the main line circuits, heretofore described, leading to the receiving instrument 2^a of Fig. 2 and passing through the vertically movable coils 46^a and 53^a, coil 46^a being included in the right hand main line circuit which is supplied with current through rheostat 16 and arm 12, while coil 53^a is included in the left hand main line circuit which is supplied 50 with current through rheostat 17 and arm

13. The currents thus passing through the coils 46^a and 53^a will, as is well understood by those familiar with telautographic apparatus, with the springs 58^a, control the position of the coils 46^a, 53^a vertically on the 55 cores 55^a of the field magnet 56^a, these coils being moved downwardly as the strength of the currents on the main lines increases, and upwardly as said currents decrease in strength. As the coils are thus moved vertically, they will, through the chains 57^a and segmental pulleys 67^a (around which two turns of the chains are taken), move the hinged pen arms 68^a, 69^a and 70^a, 71^a so as to cause the receiving pen 72^a to assume, over 60 its writing field, the same positions as those to which the transmitting tracer 6 is moved laterally by the operator from unison position or in the operation of writing the message transmitted. This operation, with the 65 construction of the receiving instrument shown, is so fully described in my prior application aforesaid, that further description thereof is deemed unnecessary here, except in so far as the combination relay 51^a, and 70 the parts controlled thereby, are concerned, which will presently be described in detail.

So far as the right hand main line circuit is concerned, it performs, during the transmitting operation, simply the function of 95 controlling the vertical movements of the coil 46^a. The left hand main line circuit, however, performs not only the function of controlling the vertical movements of its coil 53^a, but also the function of controlling, 100 through the combination relay 51^a, various local circuits in the receiving instrument, including that from battery 4^a (which is a local battery when the station is "receiving") for energizing field magnet 56^a. As 105 soon as current traverses the left main line circuit of Fig. 1, relay 51^a is, of course, energized and attracts its armature 64^a, thus closing the local circuit before referred to, from battery 4^a—consisting of wires 27^a, 59^a, 110 lock magnet 60^a, wire 61^a, field magnet 56^a, wire 62^a, contacts 63^a, 65^a, and wire 66^a, to negative pole of battery 4^a, with the result that said field magnet 56^a is energized for the operation of the coils 46^a, 53^a. Lock 115 magnet 60^a is also energized by the closing of this circuit so as to lock the master switch 3^a against movement from normal position, as fully described in my aforesaid prior application. This local circuit remains closed 120 so long as there is any current on the left hand main line wires, and as soon as the left main line circuit is broken, by shifting the switch 3^a from the position indicated in Fig. 4 to its normal position indicated in Fig. 3, 125 this local circuit is, of course, broken.

The vertical movement of the coils 46^a, 53^a controls the lateral movements of the receiving pen so that they will correspond with the lateral movements of the transmitting tracer, 130

but it is necessary also to provide means whereby the receiving pen will be caused to move to and from its writing field and to and from its resting place in unison position, 5 as the transmitting tracer is so moved by the operator. Such movements of the receiving pen are controlled by a magnet 73^a (hereinafter called the "pen lifter magnet"), the condition of which is, in turn, 10 controlled by the combination relay 51^a. The armature 74^a of this pen lifter magnet has depending arms pivotally connected at their lower ends to a bracket 75^a on which said magnet is supported, so that, as said 15 magnet is energized and deenergized, said armature will swing inwardly and outwardly over the cores of the magnet. The armature is held normally in its retracted position, from over the cores of magnet 73^a, 20 by a spring (not shown), and is provided with a rod 76^a against which the pen arms 70^a, 71^a rest. In the retracted position of the armature 74^a, and, therefore, of this pen-arm rest 76^a, the receiving pen 72^a, when at 25 unison, will lie in its resting place (an opening in an ink bottle, as described in my prior application aforesaid), and when over its writing field, will rest against the surface of the paper strip on which it is to 30 record the message received. When, however, the pen lifter magnet 73^a is energized, its armature 74^a, and, therefore, the pen-arm rest 76^a, will swing outwardly over the cores of said magnet and thereby move pen arms 35 70^a, 71^a, and, therefore, the receiving pen 72^a, outwardly so as to move said receiving pen outwardly from its place of rest at unison or away from contact with the paper strip on which the message is being recorded. 40 The energization of magnet 73^a is effected by battery 4^a, in the closed condition of the left hand main line circuit, through a branch circuit from the field magnet circuit just described, consisting of wire 77^a leading from 45 the winding of magnet 56^a to magnet 73^a, wire 78^a leading from said magnet 73^a to a contact 79^a (fixed at one end in one end of a tube 80^a and the opposite end of which contact is flexible and loose), a second contact 50 81^a rigidly fixed in the opposite end of said tube 80^a (and between which and the free end of contact 79^a there is a certain amount of looseness so that the free end of contact 79^a may have a certain amount of 55 play relatively to contact 81^a with which, however, it is normally in engagement), and wires 82^a, 83^a leading from contact 81^a to the wire 62^a of the circuit of field magnet 56^a. Tube 80^a is preferably of glass and is closed 60 to the atmosphere so as to prevent oxidation of its contacts 79^a, 81^a.

From this construction it results that on the closing of the left main line circuit, by the shifting of the master switch 3 (Fig. 1) 65 to the position shown in Fig. 4, the relay 51^a

(Fig. 2) is energized and the circuit for field magnet 56^a thus closed by the movement of contact plate 63^a into engagement with contact 65^a, as before described, the branch circuit just described through pen lifting magnet 73^a being also closed by engagement of loose contact 79^a with fixed contact 81^a. Pen lifter magnet 73^a being thus energized will attract its armature 74^a, moving it outwardly toward the front of the receiver, and as the armature 74^a is thus moved the pen rest 76^a, moving with it, will move the pen arms 70^a, 71^a, outwardly, thus lifting or withdrawing pen 72^a from its place of rest at unison. The transmitting tracer 6 being then moved from unison position to a position above the writing platen 5, the receiving pen 72^a will, following the movements of the transmitting tracer, take up a position in front of but out of contact with the record strip (not shown) in its writing field. So long as the loose contact 79^a just referred to remains in a state of rest, in engagement with fixed contact 81^a, the receiving pen will maintain the position just referred to in front of but out of contact with the record strip,—the branch circuit through the pen lifting magnet 73^a being closed by the contacts 79^a, 81^a. Means are provided, however, for, in effect, opening this branch circuit while current is on the left main line, so that the pen lifter magnet 73^a will be practically deenergized and the receiving pen thus caused to move toward and into contact with its record strip, and to thereafter move over the surface of such strip so long as the transmitting tracer remains in contact with and moves over the platen 5 or paper strip thereon. The means provided for so opening this branch circuit through the pen lifter magnet will presently be described. 105

The condition of the loose contact 79^a is controlled by the transmitting tracer 6, so that when said tracer is raised from its rest at its unison point, or is raised, from time to time, from the writing platen 5 during the writing operation, the loose contact 79^a will be in a state of rest against fixed contact 81^a and, as just described, the pen 72^a be moved and held away from its resting place at unison or from the surface of its record strip, as the case may be. When, however, the transmitting tracer 6 is lowered, from time to time during the writing operation, into contact with its record strip, this condition of loose contact 79^a with relation to fixed contact 81^a is disturbed, said loose contact at such times being in a state of agitation, with the result that the branch circuit for pen lifter magnet 73^a is repeatedly interrupted so that its armature 74^a and pen-arm rest 76^a are held retracted by the armature spring (not shown) and pen 72^a thus moved inwardly, by the resiliency of its arms 70^a, 71^a 110 into contact with its record strip or into its 115 120 125 130

resting place at unison, as the case may be, and will retain such position so long as the transmitting tracer 6 remains lowered and will thus, while in contact with its record strip, reproduce the movements of and writing performed by the transmitting tracer.

The means by which the condition of loose contact 79^a relatively to fixed contact 81^a is thus controlled by the transmitting tracer 6 will now be described. Referring particularly to Figs. 6 to 8, it will be observed that the tube 80^a is secured by a suitable socket 84^a to the center of a thin iron plate or diaphragm 85^a provided with a flange 86^a by which it is held in position on the upper end of relay 51^a. When said relay is energized by the current on left hand main line circuit, as heretofore described, it will attract and pull downwardly slightly the central portion of the diaphragm 85^a and when it is deenergized will release said diaphragm, tube 80, of course, moving with the diaphragm. So long as the current passing through relay 51^a is constant, loose contact 79^a will be in a position of rest with relation to and in engagement with fixed contact 81^a, and thus close the branch circuit through pen lifting magnet 73^a. Should, however, vibrations occur in the current passing through the relay it will be apparent that diaphragm 85^a will be rapidly vibrated, and loose contact 79^a disturbed from its normal state of rest and put into a state of vibration or agitated with relation to fixed contact 81^a, with the result that the branch circuit through pen lifting magnet 73^a will be so interrupted that said magnet will be practically deenergized and the armature 74^a thereof, as well as pen rest 76^a, therefore 40 occupy their retracted, rearward positions, thus leaving the receiving pen 72^a in its innermost position at unison, or against the surface of its record strip, as the case may be. Such vibrations in the left main line circuit are produced by the lowering of the transmitting tracer 6, as will now appear.

Referring to Fig. 1, it will be observed that the transmitting instrument is provided with an interrupter magnet 87 included in a local circuit of battery 4 consisting of wire 27 from positive pole of battery 4, contact 25, plate 26 of master switch 3, contact 24, wires 23 and 28, wire 88 to contact 89, armature 90, wire 91 leading therefrom to magnet 87, wire 92 leading thence to the primary winding 93 of the induction coil, and wires 94 and 19 leading from the latter to the negative pole of battery 4 to ground. For the purpose of avoiding sparking at the contact 89 and armature 90, as the latter is repelled, a shunt circuit 95 containing a condenser 96, is formed, from wire 88 to armature 90, around contact 89. It will also be observed that a short circuit is provided around the primary winding 93 of the induction coil,

consisting of wire 97 connecting wire 92 with a contact plate 98, pivotally mounted in a bracket 99 (from which it is suitably insulated), a contact 100 passing through but insulated from said bracket and engaging contact plate 98, and wires 101, 20, and 19, leading from contact 100 to the negative pole of battery 4. Writing platen 5 is located above bracket 99 and bears against a pin 102 passing through bracket 99 and bearing against the contact plate 98, so that when in the writing operation, platen 5 is depressed, contact plate 98 will also be depressed thereby breaking contact with contact stop 100 and breaking the short circuit around the primary winding 93 of the induction coil. With these two circuits the interrupter magnet 87 and its armature 90 are operated continuously, through one or the other, so long as the master switch 3 remains in transmitting position (Fig. 4) with its contact plate 26 connecting contacts 24, 25.

In the raised position of the transmitting tracer 6, the short circuit around primary winding 93 of the induction coil is closed by the engagement of contact plate 98 and contact 100 under the platen 5, so that the current from battery 4 does not pass through the primary winding 93 but by wires 101, 20 and 19 to the negative pole of battery 4, 95 no vibrations therefore being produced in the main line circuits, with the result that loose contact 79^a in tube 80^a (Fig. 2) above combination relay 51^a will be at rest against fixed contact 81^a and thus properly close 100 the circuit through pen lifting magnet 73^a to cause it to attract its armature 74^a and move and hold the receiving pen 72^a in its outer position away from the surface of its record strip. When, however, the transmitting tracer 6 is lowered to writing position and therefore depresses platen 5, the contact plate 98 will be depressed (by pin 102) out of engagement with contact 100, thereby opening this short circuit. The interrupter 110 current will thereupon pass, by wires 92, 94, and 19 through the primary winding 93 to the negative pole of battery 4 and thus induce vibratory currents, superposed upon the right and left hand writing currents. 115 Each time the tracer 6 is raised, primary winding 93 is short circuited. The vibratory currents thus traversing the two main line circuits, while the transmitting tracer is lowered, serve to vibrate slightly the operating parts of the receiver and thus overcome their friction of rest so that they may be more easily operated; while the vibrations in the left hand main line serve the additional function, heretofore referred to, of 120 keeping the loose contact 79^a (Fig. 2) above combination relay 51^a in a state of agitation so that the pen lifter magnet circuit is interrupted and pen lifter magnet 73^a practically deenergized with the result that its 125

armature 74^a and pen-arm rest 76^a are retracted and permit receiving pen 72^a to approach and rest against the surface of its record strip, which position it will retain, 5 reproducing on said strip the writing produced by the transmitting tracer, until the tracer 6 is again raised.

The armature 64^a (Fig. 2) of relay 51^a is of 10 large area and comparatively thick, (being preferably of the disk shape shown) so that, unlike the delicate, loose contact 79^a and tube 80^a, it is unaffected by these vibrations on the left main line circuit but, notwithstanding them, maintains contact plate 63^a in engagement with contact 65^a and thus maintains 15 the circuit from battery 4^a, for field magnet 56^a and lock magnet 60^a, closed. It will also be observed that in its normal retracted position, the free end of spring contact plate 20 63^a rests against armature 64^a, being engaged by a contact 103^a on the under side of the armature; while in its attracted or 25 raised position, the armature is moved away from spring contact plate 63^a, leaving it in engagement with contact 65^a which limits its upward movement, as shown in Fig. 2.

It will, of course, be understood from the 30 description above given of the devices for effecting the to and fro movements of the receiving pen relatively to its recording strip or place of rest at unison, and the brief description preceding it of the devices for effecting the movement of the receiving pen over its recording strip to reproduce the 35 writing performed by the transmitting tracer, that, starting with the transmitting tracer at unison or in its normal position, the first movement given it by the operator is to raise it and then move it laterally to a 40 position over the writing field of platen 5,— and it will also be understood that the receiving pen will at the same time be withdrawn from its place of rest at unison and then moved (as the tracer is moved) laterally to a position over the writing field of 45 its recording strip. The transmitting tracer being then lowered onto platen 5, the receiving pen will be moved inwardly into contact with its recording strip, and the 50 transmitting tracer being then moved over its writing platen to trace or write the message, the receiving pen will be correspondingly moved over the surface of its recording strip reproducing thereon the writing 55 performed by the tracer. When the tracer is raised to dot an "i" or cross a "t" or to make a change or correction in matter previously written or to begin a new line,—the

receiving pen will, in like manner, be moved away from its recording strip and then be 60 brought again into contact with it whenever the transmitting tracer is lowered into contact with its writing platen.

What I claim is:—

1. The combination with a main line circuit, of a second circuit, and circuit closing means controlling said second circuit and inclosed in a receptacle comprising a pair of contacts loosely engaging each other whereby, when vibrations occur in the main line 70 circuit, one is agitated relatively to the other and thus correspondingly interrupts said second circuit, substantially as described.

2. The combination with a main line circuit, of a second circuit, and circuit closing 75 means controlling said second circuit and inclosed in a receptacle closed to the atmosphere, said circuit closing means comprising a pair of contacts loosely engaging each other whereby, when vibrations occur in the main 80 line circuit, one is agitated relatively to the other and thus correspondingly interrupts said second circuit, substantially as described.

3. The combination with a main line circuit, of a relay controlled thereby, a second circuit, and circuit closing means controlled by said relay and in turn controlling said second circuit, said circuit closing means being inclosed in a receptacle closed to the 85 atmosphere and comprising a pair of contacts loosely engaging each other whereby, when vibrations occur in the main line circuit, one is agitated relatively to the other and thus correspondingly interrupts said 90 second circuit, substantially as described.

4. The combination with a main line circuit, of a relay controlled thereby, a second circuit, circuit closing means controlled by said relay and in turn controlling said second circuit, a third circuit and circuit closing means therefor also controlled by the 100 relay, said latter circuit closing means comprising a pair of contacts loosely engaging each other whereby, when vibrations occur in the main line circuit, one is agitated relatively to the other and thus correspondingly interrupts said second circuit, substantially as described.

In testimony whereof, I have hereunto set my hand, in the presence of two subscribing witnesses.

GEORGE STEELE TIFFANY.
